(57) **CLAIM**

I claim the ornamental design for a infusion pump, as shown and described.

DESCRIPTION

FIG. 1 is a front, top and right side perspective view of an infusion pump, showing my new design;

FIG. 2 is a front, top and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front perspective view with the cover in an opened state thereof.

The broken lines in FIGS. 4, 6 and 7 are included for the purpose of illustrating portions of the infusion pump that form no part of the claimed design.
